UNITED STATES PATENT OFFICE.

LOUIS LEONARD LUCE AND LEROY MATTSON, OF ABERDEEN, WASHINGTON.

INTERNAL-COMBUSTION ENGINE.

1,390,572.

Specification of Letters Patent. Patented Sept. 13, 1921.

Application filed August 5, 1920. Serial No. 401,332.

To all whom it may concern:

Be it known that we, LOUIS L. LUCE and LEROY MATTSON, citizens of the United States, residing at Aberdeen, in the county 5 of Grays Harbor, State of Washington, have invented a new and useful Internal-Combustion Engine, of which the following is a specification.

This invention relates to internal combustion engines, one of its objects being to greatly simplify the construction of an engine of this type by eliminating valves and the operating mechanism required in connection therewith, thereby reducing the 15 weight of the engine, the cost of construction, the time required to assemble the parts, and the cost of upkeep.

A further object is to increase the efficiency of the engine by eliminating loss of 20 gas through bearings, such saving of gas being the result of the use of a pump cylinder in place of the ordinary crank case compression and said pump cylinder also being advantageous in that it results in a greater 25 compression at all speeds than is possible with the usual crank case type of engine.

A still further object is to provide an engine which will set up a quick suction of fuel into the pump cylinder followed by the 30 compression and quick discharge of the fuel from the cylinder, this action serving quickly to break up or atomize the gas and render the fuel more efficient than otherwise.

35 A further object is to provide an engine in which the charging piston is so proportioned relative to the firing piston that it will handle a much greater volume of gas (approximately 25% more) than the firing 40 piston, thereby insuring thorough scavenging, recharging and cooling of the firing cylinder with purer gas than is possible with other systems.

With the foregoing and other objects in 45 view, which will appear as the description proceeds, the invention resides in the combination and arrangement of parts and in the details of construction hereinafter described and claimed, it being understood that, within 50 the scope of what is claimed, changes in the precise embodiment of the invention shown can be made without departing from the spirit of the invention.

In the accompanying drawings the preferred form of the invention has been 55 shown.

In said drawings—

Figure 1 is a section through a two cylinder engine embodying the present improvements.

Fig. 2 is a section on line 2—2, Fig. 1.

Fig. 3 is an enlarged section through a portion of a modified form of engine.

Fig. 4 is a section on line 4—4, Fig. 3.

Referring to the figures by characters 65 of reference 1 designates the crank case of the engine on which is arranged the jacket or casing 2 provided with spaced cylinders 3 each of which is provided, at its upper end, with a smaller cylinder 4. A tubular charging piston 5 is mounted for reciprocation within each of the cylinders 3 and each of these charging pistons is provided at 70 diametrically opposed points with pivot pins 6 connecting the piston to pitmen 7 75 mounted on cranks 8 carried by the shaft 9 of the engine and which shaft is journaled in the walls of the case 1. Arranged between the cranks 8 is an oppositely extending crank 10 having a greater throw and 80 which has a pitman 11 mounted thereon. This pitman extends through the central opening in the charging piston 5 and into a hollow firing piston 12 to which it is connected by a pivot pin 13 extending diametrically within the piston 12.

Fuel intake ports 14 extending from a carburetor, open into the cylinder 3 at points in line with the heads of the pistons 5 when said pistons are at the lower ends of their 90 strokes.

The heads of the pistons 12 are provided with oppositely disposed recesses or depressions 15 and 16 and exhaust ports 17 extend from the cylinders 4 to the external 95 atmosphere and are adapted to communicate with the recesses 15 when the pistons 12 are at the lower ends of their strokes. Extending from each cylinder 4 in line with the exhaust port 17 is an intake port 18 100 adapted to communicate with the recess 16 and extending from the upper portion of the cylinder 3.

It will be understood that the spaces within the cylinders 3 between the upper ends of the pistons 5 and the upper ends of said cylinders, and which spaces surround a portion of the firing piston 12, constitute the compression chambers 19 of the engine while the spaces between the pistons 12 and the 110 upper ends of the cylinders 4 constitute explosion chambers 20. Spark plugs 21 are

arranged in the heads of the cylinders 4 and can be controlled by suitable timing mechanism not shown.

It will be understood that during each 5 rotation of the shaft 9 the piston 5 in one unit of the engine will be drawn downwardly while the piston 12 will be moved upwardly. The downward movement of piston 5 will create a partial vacuum in the compression 10 chamber 19 because the piston 12 during its upward movement closes the port 18 as shown at the left of Fig. 1. This partial vacuum will continue until the piston 5 passes below the intake port 14 whereupon 15 fuel will rush into the chamber 19. As the two pistons reach the limits of their movements above mentioned the charge of fuel which has been compressed by the piston 12 in the chamber 20 will be exploded, thus 20 driving the piston 12 downwardly and at the same time causing the piston 5 to move upwardly. Piston 5 will promptly close the port 14 and will operate to compress the fuel in the chamber 19 until the piston 12 has 25 moved downwardly a sufficient distance to expose the ports 18 and 17 whereupon the compressed fuel will rush through the port 18 into the depression 16 and be deflected upwardly by the wall of the depression toward 30 the upper end of the cylinder 20, at the same time driving out the spent gases which will leave by way of port 17. The opening of these ports is only momentary as the pistons begin promptly to move back to their 35 former positions whereupon the charge which has been directed into the chamber 20 will be compressed by the ascending piston 12 while a partial vacuum is being created in the chamber 19 as before explained.

40 The pistons of the two units of the engine illustrated work oppositely to each other so that where a two cylinder engine is employed there will be two explosions during each revolution of the shaft 9. Obviously 45 the number of units can be increased so as to produce an engine of any desired size and power.

It will be apparent that a very high degree of compression can be obtained with 50 this engine, and as there is no compression in the crank case practically all waste of fuel is eliminated. Furthermore by mounting the pistons and cylinders as described the parts are thoroughly lubricated. Likewise, as before stated, the manner in which 55 the gas is worked in its passage from the carbureter to the explosion chamber insures a thorough mixing and atomizing of the gas and the highest efficiency.

60 Instead of having the charging piston made as shown at 5 in Fig. 1, the same can be made with a hollow wall open at both ends and having a transverse web between its ends, the piston being indicated at 22 in 65 Figs. 3 and 4 and the web at 23. Screws 24

are swiveled in the web 23 as indicated at 25 and are in threaded engagement with a ring 26 fitting snugly within the hollow wall of the piston. Thus it will be seen that by rotating the screws 24 by means of screw 70 drivers or the like the ring 26 can be adjusted toward or from the open end of the piston, thus to reduce or increase the area of the compression chamber 19 which, obviously, opens into the hollow wall of the piston 22. 75 By providing an adjustable compression chamber the structure can be regulated at will to secure the best results in different types of engines.

What is claimed is:

1. A two cycle internal combustion engine including a tubular charging piston, a firing piston mounted for movement therein, a cylinder for each piston, means for reciprocating the pistons in opposite directions respectively, an intake port controlled by the charging piston, means controlled by the firing piston for establishing communication between the cylinders and with the external atmosphere, the cylinder of the tubular piston forming a compression chamber, and means under the control of the user for varying the capacity of the compression chamber. 80

2. A two cycle internal combustion engine 95 including a tubular charging piston, a firing piston mounted for movement therein, a cylinder for each piston, means for reciprocating the pistons in opposite directions respectively, an intake port controlled by the charging piston, means controlled by the firing piston for establishing communication between the cylinders and with the external atmosphere, the cylinder of the tubular piston forming a compression chamber, and adjustable means within the tubular charging piston for varying the capacity of the compression chamber. 100

3. A two cycle internal combustion engine including a tubular charging piston having 110 a hollow wall open at its ends, a firing piston mounted for movement within the tubular charging piston and surrounded thereby, a cylinder for each piston, the cylinder of the charging piston forming a compression 115 chamber, said chamber opening into the hollow wall of the charging piston, means for reciprocating the pistons in opposite directions respectively, an intake port controlled by the charging piston, means controlled by 120 the firing piston for establishing communication between the cylinders and with the external atmosphere, and means adjustably mounted within the hollow wall of the charging piston for varying the capacity of 125 that portion of the space in the wall of the piston in communication with the compression chamber.

4. A two cycle internal combustion engine including a tubular charging piston having 130

- a hollow wall open at its ends, a firing piston mounted for movement within the tubular charging piston and surrounded thereby, a cylinder for each piston, the cylinder of
5 the charging piston forming a compression chamber, said chamber opening into the hollow wall of the charging piston, means for reciprocating the pistons in opposite directions respectively, an intake port controlled
10 by the charging piston, means controlled by the firing piston for establishing communication between the cylinders and with the external atmosphere, and means adjustably mounted within the hollow wall of the
15 charging piston for varying the capacity of that portion of the space in the wall of the piston in communication with the compression chamber, said means including a ring slidably mounted within and engaging the walls of the space within the wall of the 20 charging piston, and swiveled screws within said charging piston and extending through the ring.
- In testimony that we claim the foregoing as our own, we have hereto affixed our signatures in the presence of two witnesses.
